UNITED STATES PATENT OFFICE

ARTHUR GALBRAITH, OF ASH GROVE, MISSOURI

CHIN SUPPORT

Application filed September 27, 1928. Serial No. 308,861.

This invention relates to chin supporters employed by undertakers for holding the lower jaw and mouth of a person after death, in their natural positions until "rigor mortis" has set in or until the stiffening effect of the embalming fluid has taken place.

An important object of the invention is to provide a device of this character which may be positioned accurately in such a way that it will not slip from its adjusted position.

A further object of the invention is the provision of an adjustable member movable over a threaded supporting rod and held in its positions of adjustment by means of a nut which may also be operated for making a delicate adjustment.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a perspective view illustrating the application of the device.

Figure 2 is an enlarged side elevational view of the device.

Figure 3 is a rear elevational view thereof.

Figure 4 is a sectional view taken on line 4-4 of Figure 2.

Referring to the drawing in detail the device includes a main or supporting rod 5 which is threaded throughout its length, and provided with flat surfaces 6, for purposes to be hereinafter more fully described.

An enlargement 6' is formed at one end of the rod 5 and provides a support for the nose engaging prongs 7, which extend therefrom, and as shown these prongs are curved outwardly as at 8 and rearwardly in spaced parallel relation with each other as at 9, the ends of the prongs being provided with ball shaped enlargements 10.

Mounted on the rod 5 is a laterally extended chin piece 11 formed with an oblong opening 12 to accommodate the rod 5 in such

a way that certain rocking movement of the chin piece 11 will be permitted, but rotary movement of the chin piece with respect to the rod 5 will be prevented, thereby insuring accurate adjustment of the device.

Pivotedly mounted at the free end of the chin piece 11 is a chin rest 13 which is slightly curved to conform to the shape of the chin. The adjusting nut is indicated by the reference character 14 and operates on the threaded rod 5, the adjusting nut being provided with a knurled portion 15 so that it may be readily and easily operated by the person using the chin support.

As shown, this nut 14 engages the under-surface of the chin piece 11 so that as the screw is rotated, movement is imparted to the chin piece to move the chin piece towards the nose prongs supported at the upper end of the rod 5.

In use, the nose engaging prongs are inserted in the nostrils, and the chin piece and chin rest are positioned to engage the chin, whereupon the nut 14 is operated to move the chin piece longitudinally of the rod 5 until the mouth is closed and the mouth and chin are in their natural positions.

The device remains in this position until "rigor mortis" sets in, whereupon the device may be removed.

Owing to the construction shown and described, it will be obvious that the device may be accurately positioned with assurance that the device will not slip after such positioning.

I claim:

1. A chin supporter including a threaded rod, a member to be positioned in the nostrils, at one end of the rod, a chin piece movable longitudinally of the threaded rod, a nut operating in the threaded rod for moving the chin piece longitudinally of the threaded rod, and a chin rest on the chin piece.

2. A chin supporter including a threaded rod, a nostril engaging member at one end of the rod, a chin piece movable longitudinally of the rod, and an adjusting nut on the rod and contacting with the chin piece for moving the chin piece longitudinally of the rod.

3. A chin supporter including a rod, nostril engaging members at one end of the rod,

said rod having threads and having flattened surfaces, a chin piece having an opening to accommodate the rod, said opening having flattened surfaces to engage the flattened surfaces of the rod to prevent rotary movement of the chin piece, and an adjusting nut on the rod for adjusting the chin piece longitudinally of the rod.

5 In testimony that I claim the foregoing as
10 my own, I have hereto affixed my signature.
ARTHUR GALBRAITH.
